(57) **CLAIM**

The ornamental design for a hair extension, as shown and described.

DESCRIPTION

FIG. 1 is a top, front, right side perspective view of a hair extension.

FIG. 2 is a front elevation view of the hair extension.

FIG. 3 is a rear elevation view of the hair extension.

FIG. 4 is a left side elevation view of the hair extension.

FIG. 5 is a right side elevation view of the hair extension.

FIG. 6 is a top plan view of the hair extension.

FIG. 7 is a bottom plan view of the hair extension; and,

FIG. 8 is a top, front, right side perspective view of the hair extension in a rolled configuration.

The broken lines are shown for illustrative purposes and form no part of the claimed design.
